CLAIM

The ornamental design for an analysis system as shown and described.

DESCRIPTION

FIG. 1 is a front perspective view of an analysis system;
FIG. 2 is a rear view of the analysis system;
FIG. 3 is a top view of the analysis system;
FIG. 4 is a bottom view of the analysis system;
FIG. 5 is a back perspective view of the analysis system;
FIG. 6 is a second front perspective view of the analysis system;

FIG. 7 is a first side view of the analysis system; and,
FIG. 8 is a second side view of the analysis system.

The broken lines in the drawings illustrate portions of the analysis system that form no part of the claimed design.
